UNITED STATES PATENT OFFICE.

ARTHUR GIESLER, OF DAYTON, OHIO, ASSIGNOR TO THE STILWELL-BIERCE & SMITH-VAILE COMPANY, OF SAME PLACE.

AMMONIACAL-GAS COMPRESSOR.

SPECIFICATION forming part of Letters Patent No. 602,802, dated April 19, 1898.

Application filed October 3, 1895. Serial No. 564,502. (No model.)

To all whom it may concern:

Be it known that I, ARTHUR GIESLER, of Dayton, county of Montgomery, State of Ohio, have invented a new and useful Improvement in Ammoniacal-Gas Compressors; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to improvements in gas-compressors of the class used in connection with ice-making and refrigerating machines.

The object of the invention is to provide a compressor that is especially adapted to ammoniacal gas and which has a high degree of efficiency. With the attainment of these objects in view the improvements have reference to the construction of the head, upon which the cylinder is mounted and through which the gas is introduced to and from the valves and which enables the water-jacketing of the entire cylinder and the upper valves.

Referring to the annexed drawings, forming a supplemental part of this application, Figure 1 is a side elevation of an ammoniacal-gas compressor constructed in accordance with my invention. Fig. 2 is an enlarged sectional elevation of the upper part on the line $\alpha\alpha$ of Fig. 1. Fig. 3 is a vertical section through the cylinder and head, taken on an axial line at a right angle to Fig. 2. Fig. 4 is a horizontal section on the line yy of Fig. 3.

In the specification to follow similar characters of reference will be used to denote corresponding parts in the different views.

The letter A designates the housing, the summit of which is surmounted with a head A'. This head is constructed with a view to the accommodation of a lower set of valves to be hereinafter referred to, and to this end the said head is constructed with two inwardly-tapering openings aa , diametrically opposite each other and inclining upwardly, substantially as is shown in Fig. 2. The upper terminal of said head is also constructed with a circular cavity b , which forms the lower end of the gas-chamber C' when the cylinder C is

mounted. There is also a central opening in said head through which the piston-rod passes and which terminates in a stuffing-box.

B' designates the head of the cylinder, which is securely mounted on the upper end of said cylinder and which is also provided with two diametrically-positioned valve-openings $a'a'$, substantially of the form and angle shown in the drawings and similar to those in the head A'. The lower side of the cylinder-head B' is also constructed with a circular cavity b' of the same dimensions as those of the cavity in the head A' and which forms the upper rounded terminal of the gas-chamber C'. 65

It will be noted that the piston-cylinder is open at both ends; but when its ends are inclosed by the respective heads A' and B' there is a continuous gas-chamber formed, both ends of which are uniformly rounded and conform to the rounded ends of the piston. Communicating with the central part of this chamber are a series of ports u , that extend around the cylinder and discharge gas from an annular chamber v . This latter chamber 75 receives the gas under suction from an inlet-passage s , that extends vertically on the exterior of the cylinder on the inside of the water-jacket, as shown in Fig. 3, and discharges gas to the suction-valves i and i' 80 through the ports $c c$. The passage s is fed from the main inlet or suction pipe d , which enters the head A' and communicates with the lower part of said passage s .

B designates the piston, which is shown 85 partly in section in Fig. 2 and which is connected to a piston-rod B'', that passes through a series of packing-rings f , inclosed in the box F and maintained in position by a gland F'. The downwardly-projecting portion F, 90 forming said stuffing-box, is an integral part of the head A' and is surrounded by a downwardly-extending water-jacket that keeps said stuffing-box at a desirable temperature.

e, e', e^2 , and e^3 designate bushing placed in 95 the valve-openings a and a' and which provides seats for the several valves. Two of these valves—to wit., the suction or inlet valves i and i' —are located on the suction side of the compressor and communicate with 100 the gas-chamber C' at opposite ends of the cylinder. The pressure or outlet valves i^2

and i^3 are similarly located in the discharge side of the compressor.

The letter g designates a series of caps that inclose the outer ends of the valves and are made secure within the valve-openings a and a' .

d designates the suction or inlet pipe through which the ammoniacal gas is inducted to the inlet-valves through ports c c' and thence to the chamber C' . The discharge-pipe d' enters the head A' and communicates with the passage s' and valves i^2 and i^3 through ports c c' .

From the foregoing description it will be seen that upon a downward stroke of the piston gas will be inducted through valve i under suction to the chamber C' and also through the ports u when the piston has moved far enough to uncover said ports u sufficiently to enable the gas to pass into the said chamber. The piston acts as an automatic valve in connection with these ports by uncovering them upon each stroke. This is a material advantage, as the compressor is thereby enabled to run faster, and the efficiency is consequently greatly increased. For example, when the pressure following the piston is less than the suction pressure in the main suction or inlet pipe (which is the case whenever the piston travels faster than the gas can follow) a sufficient amount of gas cannot be inducted through the suction-valves to drive the piston at a desirable speed. This deficiency in pressure is compensated for by the admission of gas through the ports u . Owing to the construction of the suction-valves at the ends of the cylinder being essentially small, it is not possible to obtain through them an amount of gas necessary to run the compressor at a desirably high rate of speed; or, in other words, it is not practicable to construct these valves large enough to admit through them an amount of gas equal to that entering through the ports u in addition to the amount of gas entering through said valves as they now appear. The supplemental gas-chamber v , with the inlet-ports u , are essential features of this invention.

To more clearly define the operation of admitting the necessary amount of gas to the cylinder, it is stated that when the piston travels at a comparatively slow rate of speed the suction-valves are permitted to remain open a longer time to fill the space in the cylinder with gas. During this period the pressure behind the piston becomes equal to that at the ports u , and there is consequently no gas inducted through said ports; but as the speed of the piston increases the suction-valves are permitted to remain open a shorter length of time in which to fill the space in the cylinder. In this event the pressure behind the piston does not equal that at the ports u , and the result is gas is admitted through said ports as they are uncovered by the piston, which compensates for the deficiency at the suction-valves. It will therefore be seen that

the ports u become, in connection with the piston, practically an automatic valve, which is controlled alone by the speed of the piston, discharging gas into the cylinder in proportion to the speed of said piston. The gas thus introduced to the chamber C' will be discharged under pressure through the outlet-valve i^2 upon the return or upward stroke of the piston. During said downward stroke of the piston gas that was previously inducted through the suction-valve i and ports u into the chamber will be discharged through the outlet-valve i^3 to the discharge-pipe d' , through which it is carried to the freezing coils. (Not shown.) The several valves seat easily under the pressure of helical springs o . The piston is provided with two series of sealing-rings p , that prevent any passage of ammonia in a gaseous or liquefied state from one end of the chamber to the other, and the ports u are sealed by said rings as soon as the straight surface of the piston covers them.

From the construction exemplified in Fig. 2 it will be seen that the lower set of valves are easily accessible, there being nothing inclosing them but their caps. The upper set of valves are only inclosed in addition to their caps by the water-jacket B^4 . The trouble of detaching the various parts of the compressor in order to gain access to the valves from time to time is removed by this construction. The stuffing-box and head A' are cooled by the water-chamber t , which has a detachable cover t' . This chamber t communicates with the water-chamber r through passages r' , (shown in broken lines,) and a continuous circulation of water is maintained in both chambers, that keeps the entire parts cool. The water is introduced through inlet-pipe x and passes out from the chamber t through outlet-pipe x' . (Shown in dotted lines.)

It is apparent from the construction shown in Figs. 2 and 3 that the gas for the upper and lower valves and the water for the upper and lower jackets enter and leave the pump through the head A' . This enables the parts to be easily detached whenever it becomes necessary and also admits of the entire pump being water-jacketed.

Having fully described my invention, I claim and desire to secure by Letters Patent—

1. In a gas-compressor, the combination of a head A' , a cylinder mounted on said head, inlet and outlet valves at the upper and lower ends of said cylinder, passages s and s' in the wall of the cylinder communicating with the suction and discharge pipes through said head, and with the upper valves, and a central annular gas-chamber around the cylinder and communicating with said passages s , and with the cylinder through a series of ports u which are controlled by the piston, and through which, gas is admitted to the cylinder when the pressure behind the piston becomes less than the pressure at said ports,

whereby the said piston may be maintained at a high rate of speed, substantially as described.

2. In a gas-compressor, a cylinder provided with an inlet and an outlet valve communicating with the upper end thereof, inlet and outlet passages s for said valves extending from the lower end of the cylinder, and a central annular gas-chamber communicating with the passages s and s' , and with the cylinder, in combination with a head upon which the cylinder is mounted, and through which, an inlet and outlet is afforded for the upper valves through the passages s and s' , and inlet and outlet valves in said head communicating with the lower end of the cylinder and having an inlet and outlet also through the head, substantially as described.

3. In a gas-compressor, the combination with a cylinder having inlet and outlet passages s and s' extending up the sides thereof, and an annular gas-chamber around the central part thereof communicating with the cylinder through a series of ports which are controlled by the piston and through which, gas

is admitted to the cylinder when the pressure behind the piston becomes less than the pressure at said ports, inlet and outlet valves communicating with the upper ends of said passages s and s' and with the cylinder, and a water-jacket inclosing said cylinder and valves, of a head A' having an integral stuffing-box F, and upon which the said cylinder and water-jacket are mounted, and into which the main inlet and outlet pipes enter and communicate with the passages s and s' , inlet and outlet valves in said head communicating with the lower end of the cylinder and with the main inlet and outlet pipes, and a water-jacket in said head to cool the stuffing-box and lower valves and through which a circulation of water is maintained in water-jacket surrounding the cylinder and upper valves, substantially as described.

In testimony whereof I have hereunto set my hand this 24th day of September, 1895.

ARTHUR GIESLER.

Witnesses:

R. J. McCARTY,
IRVING LONGENECKER.

It is hereby certified that in Letters Patent No. 602,802, granted April 19, 1898, upon the application of Arthur Giesler, of Dayton, Ohio, for an improvement in "Ammoniacal-Gas Compressors," errors appear in the printed specification requiring correction, as follows: Page 3, line 7, the word and reference letter "passages *s*" should read *passages s and s'*, and same page, line 10, the words and reference letters "passages *s* and *s'*" should read *passage s*; and that the said Letters Patent should be read with these corrections therein that the same may conform to the record of the case in the Patent Office.

Signed, countersigned, and sealed this 3d day of May, A. D., 1898.
